UNITED STATES PATENT OFFICE.

GRANVILLE F. THAYER, OF PROVIDENCE, RHODE ISLAND, ASSIGNOR TO M AND T
BUTTON COMPANY, OF BOSTON, MASSACHUSETTS, A CORPORATION OF MASSA-
CHUSETTS.

BUTTON-CARDING MACHINE.

1,273,552.

Specification of Letters Patent. Patented July 23, 1918.

Application filed March 6, 1917. Serial No. 152,777.

To all whom it may concern:

Be it known that I, GRANVILLE F. THAYER, a citizen of the United States, residing at Providence, in the county of Providence, State of Rhode Island, have invented certain new and useful Improvements in Button-Carding Machines, of which the following is a specification.

My invention is an automatic machine for 10 carding buttons or like articles to assemble them in convenient form for handling in the various processes of their manufacture. The object of my improvement is to provide a mechanism for feeding the buttons, or similarly-shaped small articles, from a supply, and for affixing them to cards or continuous strips of sheet-material whereby they may be assembled in close relation with their surfaces exposed to receive a finishing treatment, such as enameling or japanning by 20 brush, spray or roll.

My improved machine operates to feed and arrange the buttons in parallel alignment and to attach them to the card or strip 25 in rows by inserting their eyes therethrough. As before stated, the particular purpose of the invention is to provide means for carding the buttons to facilitate their handling during the operation of finishing them, but 30 the apparatus is also adapted for attaching the buttons to cards in their finished form to present them in merchantable shape for commercial use or sale.

The invention is fully explained in the 35 following specification, illustrated by the accompanying drawings, in which like reference characters designate like parts. In the drawings:—

Figure 1 is a front elevation of the machine showing the feed-rolls for the paper-strip or card and the reciprocable plungers for applying the buttons thereto, with a general view of the operating-mechanism therefor;

Fig. 2, an end view of the same looking in the direction indicated by the arrow α , Fig. 1;

Fig. 3, an enlarged, detail view of the opposite end of the machine showing the 50 spring-pressure means for the feed-rolls, and also illustrating the vibrator-mechanism which acts against the button-feeding raceways to agitate the latter to prevent the buttons from sticking or clogging therein.

Fig. 4, an enlarged, detail view of a portion of the operating-mechanism for the raceway-vibrators;

Fig. 5, an enlarged, vertical, sectional view taken on the line X—X of Fig. 1, looking in the direction indicated by the arrow α , and 60 showing the button-controlling and setting devices;

Fig. 6, a detail view of the button-affixing means, with one of the button-setting plungers illustrated in the act of inserting the 65 button-eye through the card;

Fig. 7, a transverse, sectional view of the button-feeding chute or raceway, showing the means for holding and guiding the buttons therein;

Fig. 8, a similar view showing a modification in the form of the raceway to adapt it 70 for buttons of a different style;

Fig. 9, a detail view of a modified form of the button-advancing means or feed-plate 75 which projects the button forward from the raceway into position to be operated upon by the setting-plunger;

Fig. 10, a plan view showing the several 80 button raceways and the relation of the button feed-plate thereto, and also illustrating the button-locating gage or stop and its operating-mechanism;

Fig. 11, a vertical elevation of the button 85 stop-pins which operate to hold the feeding buttons back in the raceway while the ones previously projected therefrom are being set, and also showing the tension-fingers which engage the tops of the buttons to hold them erect; and

Fig. 12, an enlarged, detail view of the 90 tension-fingers.

The machine in general.—My new apparatus comprises several coördinated mechanisms for performing the various functions 95 of feeding and affixing the buttons to the card or strip as follows: First, the intermittently-actuated feed-rolls for feeding the cardboard or paper strip through the machine; second, the raceways or chutes for 100 delivering the buttons into the machine; third, the button-feeding devices for projecting the buttons from the raceways into position to be affixed to the card or strip; fourth, the button-controlling means for 105 regulating and timing the projection of the buttons from the raceways; fifth, the button-gage for alining and holding the but-

tons in position to be operated upon by the setting-means; sixth, the button-setting means for affixing the buttons in place on the card; and seventh, an auxiliary device 5 for vibrating the button-feeding raceways, which, though not essential to the operation of the other mechanisms, is provided to insure an uninterrupted feed of the buttons by preventing them from sticking or clogging 10 in the raceways.

The card- or strip-feeding means.—Referring first to Figs. 1 and 2, the main frame of the machine comprises two uprights or standards F, F' mounted on any 15 suitable base or bed-plate A and provided with bearings for the horizontal cross-shaft S. The shaft S projects through its bearings in the uprights F, F' and is connected to rotate two stud-shafts S', S' by means 20 of the pairs of intermeshing gears s, s' at their ends. Secured rotatively to the shaft S between the uprights F, F' is the lower feed-roll R, the surface of which is scored with relatively narrow, circumferential 25 grooves r for a purpose as later explained. Referring to Figs. 1 and 5, the stud-shafts S' carry two relatively narrow, disk-like feed-rolls R', R', at their inner ends which are adjustable vertically in relation to the 30 roll R in accordance with the thickness of the cardboard or paper-strip being fed. For this purpose the bearings for the shafts S', S' are slidable up and down in the frame-members F, F'. 35 As shown in Figs. 1 and 3, the bearings for the shafts S', S' comprise two blocks 2, 2 fitted to slide in the vertical slots 3 in the uprights F, F' and provided at their lower ends with the bearing-seats 4. Let 40 into cross-slots 5 in the sides of the vertical slots 3 are fixed blocks 6 between which and the bearing-blocks 2 are pressure-springs s', see Fig. 3. The lower ends of the springs s' seat in recesses 7 in the bearing-blocks 2 45 and their upper ends are engaged by the flanged caps or washers 8 fitted to bores 9 in the fixed blocks 6. Screwed down through the fixed blocks 6 are set-screws 10 which bear against the caps or washers 8 50 and are locked from unwarranted turning by the check-nuts 11. The springs s' act to hold the upper rolls R', R' bearing against the margin of the card C or other strip passing over the roll R, and the pressure 55 exerted thereby may be regulated by adjusting the screws 10 to vary the tension of the springs. On the end of the lower feed-roll shaft S is a hand-wheel Z, held in place by the nut z, which serves as a means for turning 60 the rolls manually in entering the card or strip between their peripheries. As shown more particularly in Fig. 5 the cardboard or paper stock C feeds into the machine from the rear where it may be supplied from a roll, not herein shown, or may

issue from any other source as preferred. As the card or strip C passes between the feed-rolls R and R', R', its side edges travel in the slots 12 of two grooved guideways 13. As shown in Fig. 1, the guideways 13 may 70 be constructed in the form of cleats or strips fastened to the sides of the frame-members F, F' and cut away at the top and bottom at 14, see Fig. 5, to clear the peripheries of the rolls R, R'. From the guideways 13 75 the card C feeds out of the machine across inclined guides or strip-members 15, see Fig. 2, in the manner as more fully explained hereinafter.

The operating-mechanism for the feed-rolls.—The feed-rolls R, R' are rotated with an intermittent, step-by-step motion through the operation of means as next described: Journaled in bearings f, f' at the top of the frame-members F, F' is a horizontal shaft 85 P, see Fig. 1, which may be considered the main drive-shaft of the machine. The shaft P is driven from any convenient source of power by means of a belt, not here shown, passing over the pulley P' on its end, or 90 through any other suitable arrangement such as gears or chain-sprockets. Referring to Figs. 1 and 2, the right-hand end of the shaft P carries a crank-disk D secured rotatively therewith by means of the set-screw d. The 95 side of the disk D is provided with a radially-extending dove-tailed slot 16 in which a block 17 is fitted to slide. The block 17 carries a crank-pin 18 projecting from its side and is adjustable in relation to the axis 100 of the disk D to vary the throw of the crank. The adjusting-means for the crank-pin 18 may be of any convenient arrangement and, as shown in Fig. 2, comprises a screw 19 engaging a transverse, threaded hole in the 105 block 17. A flange or collar 20 on the screw 19 engages a cross-slot 21 in the disk D to take the end-thrust in one direction, while a pin 22 driven into the disk and engaging 110 a peripheral groove 23 in the screw acts against the opposite thrust and also retains the screw in place. The end of the screw 19 projects slightly beyond the periphery of the crank-disk D and is slotted to receive a screw-driver. By turning the screw 19 the 115 block 17 may be slid in its slot 16 to adjust the crank-pin 18 toward or away from the center of the disk D to regulate its eccentricity or throw.

A link or connecting-rod L is pivoted at 120 one end to the crank-pin 18 with its opposite end pivotally connected at 24 to the side of an arm or lever L'. The lever L' is pivotally mounted on the lower feed-roll shaft S abutting the side of a toothed ratchet-wheel or 125 disk M, which latter is secured rotatively to the shaft S adjacent the gear s. At the outer extremity of the lever L' is a pawl N pivoted on a pin 25 to adapt its lower end or toe to engage with the teeth of the ratchet 130

M. A flat spring 26 fastened to the end of the lever L' at 27 acts against the pawl N to maintain it in engagement with the ratchet M while allowing it to ride across the teeth. 5 On the opposite side of the ratchet M is a similar pawl N' pivoted on a stud 28 screwed into the frame-member F', and maintained in engagement with the teeth of the ratchet M by a spring 29. When the 10 power-shaft P is rotated to drive the machine the crank-disk D acts through the link L to rock the lever L' to cause its pawl N to turn the ratchet M. An intermittent motion is thus imparted to the shaft S, which, 15 acting through the gears s, s will effect rotation of the feed-rolls R, R' in the direction indicated by the arrow a, Fig. 2. As before explained, the rolls R, R' feed the strip or card C forward from its supply with a 20 step-by-step movement, the extent of which may be regulated by adjusting the throw of the crank-pin 18.

The button-delivering means.—Referring next to Figs. 2 and 5, at the rear of the machine is a series of inclined chutes or raceways E, E for conveying the buttons B into position to be operated upon by the affixing devices. As herein illustrated the machine is provided with twelve raceways E for feeding the buttons twelve in a row, but a greater or less number could be employed if desired. Each raceway is constructed in the form of a grooved bar or track E, see Fig. 7, having a relatively narrow, longitudinally-extending 30 slot e in which the wire-loops or eyes b of the buttons slide. The tops of the raceways are preferably concaved or beveled inwardly to receive the bottom of the button-head while providing a clearance at the point 35 where the eye b is joined thereto. The purpose of this is to prevent irregularities or projections on the base of the button from binding in the slots e, and also to reduce the friction on the sides of the button-eye b as 40 it slides through the raceway. Fig. 8 shows a modified form of the raceway E having its top more deeply concaved to provide clearance for the boss or projection b' with which some styles of buttons are formed. 45 Supported above each raceway and extending longitudinally thereof, is a thin guard-strip E' fastened to its side by the bent ears 50 held by the screws 31, see Figs. 2 and 7. The guard-strip E' overhangs substantially 55 the whole length of the raceway E and is designed to prevent the buttons from jumping out or being otherwise displaced during their travel through the slot e. The several raceways E are supported near their lower 60 ends by a strip or brace 32, see Fig. 5, which extends across the width of the machine and is attached to the uprights F, F' or mounted on the machine-frame in any other convenient manner. At their upper ends the raceways E communicate with hoppers or other

containers in which the buttons are placed to deliver them to the machine. These hoppers are not herein shown or described as they may be of any well known construction such as generally used on button-sewing machines or like apparatus. Suffice it to state that the buttons are delivered from the hoppers to the raceways in a substantially continuous supply so as to maintain an uninterrupted feed to the affixing-devices of the 70 machine. The buttons feed through the inclined raceways under the action of gravity and at the delivery-ends thereof are brought into a substantially upright position to be projected forward into proper relation with 75 the strip or card C. As shown in Fig. 5 the raceways are curved at their lower ends for this purpose so that the buttons assume a substantially upright position as they issue therefrom. 80

The button feeding- and positioning-means.—The means for projecting the buttons B from the raceways E and feeding them into position to be affixed to the card C comprises essentially a slotted feed-plate 90 or apron H, shown in detail in Figs. 5 and 10. The plate H is supported at its rearward edge by hinge-like collars h mounted to turn on a horizontal rod J. The rod J is carried at the lower ends of two arms J', 95 J' which extend downwardly from a rock-shaft K. Extending forwardly from the ends of the rock-shaft K are two arms K', K' which carry rollers k, k at their outer ends, adapted to engage the faces of two 100 cams O, O fast on the ends of the drive-shaft P, see Figs. 1, 2 and 5. The rollers k are held against the cams O by means of springs j, j fastened to the arms J', J' and anchored at their opposite ends to the studs 105 j', j' driven into the frames F, F', see Figs. 2 and 3. As the cams O rotate with the shaft P they act on the rollers k to rock the arms K' to oscillate the shaft K. The oscillation of the shaft K is transmitted 110 through the arms J' to travel the rod J with a forward-and-back motion which reciprocates the feed-plate H beneath the ends of the raceways E. As shown in Figs. 5 and 10 the feed-plate H is fastened in the slotted lugs 33, projecting from the hinge-collars h on the rod J, by means of the screws 34. The forward edge of the plate H slides across the beveled under sides of the raceways E and is maintained bearing thereagainst by tension-springs 35 coiled around the rod J. Referring particularly to Fig. 10, the inner ends 36 of the springs 35 are held by collars 37 secured fast on the rod J by means of the set-screw 38, while their 120 opposite ends 39 are bent outwardly to reach in under the rear edge of the plate H, as shown in Fig. 5. In the outer edge of the plate H are a plurality of slots h' adapted to receive the shanks or eyes b of the but- 130

tons B as they project through the slots *e* in the raceways E. Referring to Fig. 9, the plate H is here shown as having the sides of the slots *h'* cut away on top to clear the 5 teat or boss *b'* on buttons of that type previously referred to in connection with Fig. 8. On the under side of the plate H are two flat springs I, I fastened in place by the screws *i* and bowed out between their ends 10 to adapt them to bear against the top of the card or strip C when the plate is projected forward into the position illustrated in Fig. 6. The purpose of the springs I is to hold the card or paper C flat as it feeds through 15 the guideways 13 to prevent it from buckling or bending upward at the center.

The button feed-regulating devices.—Referring still to Fig. 5, the guard-strips E' which overlie the slotted raceways E are cut away at their lower ends and displaced by a series of thin spring-fingers T fastened to a portion of the supporting-bar 32 by means of the screws 39. As shown in the detail view, Fig. 12, the lower end of 20 each spring T is slotted at *t* to form a sort of fork, the sides of which bear against the top of the button B as it delivers from the raceway E, see Fig. 5. The purpose of these 25 spring-fingers T is to prevent the buttons from riding up out of the slots *e* in the raceways E or from being canted or tilted out of position as their shanks or eyes *b* are engaged by the feed-plate H. After each set 30 of buttons has been projected forward from the ends of the raceways E the spring-fingers T are lifted away from interference with the other buttons in the lower end of the raceways so as to allow them to feed down into place. The means for lifting the 35 ends of the fingers T consist of a series of T-headed pins U held in a reciprocable frame U' extending across the machine as shown in Fig. 11. The pins U are held fixedly in vertical holes 40 in the frame U' by means 40 of the set-screws 41, and their lower ends are slotted on opposite sides to provide the T-heads *u*. Each pin U projects downwardly between two fingers T and their heads *u* underlie the overhanging fin-like 45 edges *t'* of the fingers to adapt them to engage therewith, see Fig. 12. The frame U' is adapted to be reciprocated vertically, to cause the pins U to act to lift the spring-fingers T, by means of a pair of cams V, V 50 on the drive-shaft P, see Figs. 5 and 11. As here shown the frame U' is supported at the lower ends of two rods 42, 42 which slide in the vertical bores 43, 43 of a crosshead W extending between the side-frames F, F', 55 see Fig. 1. The crosshead W carries the plungers *w* which operate to set the buttons on the card and has a reciprocating motion for this purpose, as more fully explained hereinafter. At the top of the rods 42, 42 60 are rollers *v*, *v* bearing against the periph-

eries of the cams V, V and suitable springs 44, see Fig. 5, anchored to the crosshead W at 45 and connected to the frame U' at 46 tend to raise the frame to maintain the rollers in engagement with their cams. 70

Referring now to Figs. 6 and 11, the frame U' also carries a set of spring-operated plunger-pins Y, equal in number to the whole number of button-raceways on the machine. As illustrated in Fig. 11 75 there are twelve pins Y arranged in alignment with the fixed pins U and so spaced as to adapt their lower ends to project through the slots *t* in the tension-fingers T. The pins Y are mounted to slide in vertical 80 holes 48 in the frame U', and screwed onto their upper ends are stop-collars 49 held in place by the checknuts 50. Adjacent their lower ends the pins Y are formed with enlargements or flanges *y*, between which and the bottom of the frame U' are coiled 85 springs 51. The springs 51 act to maintain the pins Y projected downwardly to the limit allowed by their stop-collars 49, and by adjusting the collars the vertical position of the pins may be varied to regulate 90 the relation of their lower ends to the tops of the buttons in the raceways E. The purpose of the pins Y is to serve as stops to check the feeding movement of the buttons 95 B in their raceways while one set or row of buttons issuing therefrom is being affixed to the card. Figs. 6 and 11 illustrate the frame U' in its lowermost position and, as shown particularly in Fig. 6, the 100 rounded ends of the pins Y will then engage the lowermost buttons B in the raceways E to prevent them from further movement until the buttons being operated upon are set in place. The springs 51 allow a 105 vertical, sliding action of the pins Y in the frame U' and provide for a yielding engagement between their ends and the tops of the buttons to compensate for irregularities in the shape or variations in the thickness of the latter. After each row of buttons has been affixed to the card C the frame 110 U' is raised slightly through the action of the cams V and springs 44 to withdraw the pins Y, whereby another set of buttons may feed down to the ends of the raceways E. This upward movement of the frame U' to withdraw the pins Y occupies but an instant of time, being provided for by the slight depressions *v* in the cams V across 115 which the rollers *v* travel, the timing of the movement and coaction of the button-controlling devices being more fully explained hereinafter. 120

The button-setting gage.—Extending 125 across the machine between the two upper feed-rolls R', and in front of the lower ends of the raceways E, is a stop-gate or gage G for alining and locating the buttons in position to be set in a straight row across 130

the card C. The gage G is constructed in the form of a rectangularly-shaped bar supported at its ends by two swinging arms g, g as shown in Figs. 5, 6 and 10, this part 5 of the mechanism being omitted from Fig. 1, however, to clarify the showing of the other parts. The arms g which support the gage G are pivoted to the lower ends of two rocker-arms 52, 52 secured fast on a rock-shaft G' which is journaled in bearings in the frame-members F, F', see Figs. 1 and 2. Extending horizontally from the rock-shaft G' is an arm 53, shown in Figs. 2 and 5, to the outer end of which is fastened a 10 spring 54 anchored at its opposite end to a pin 55 driven into the side of the left-hand frame-member F. The spring 54 tends to rock the arm 53 downwardly to carry the arms 52 into position to maintain the gage 15 G in close proximity to the ends of the raceways E, whereby the buttons B are held against issuing therefrom until ejected by the feed-plate H. An adjusting screw 56 screwed down through the arm 53 bears at 20 its end against the curved edge of the frame-member F, see Fig. 2, to limit the movement of the rock-shaft G' under the action of the spring 54. The screw 56 is held against unwarranted turning by a 25 check-nut 57 and by loosening this and adjusting the screw the gage G can be set in proper relation to the delivery ends of the raceways.

Referring particularly to Fig. 5, the arms 30 g which support the gage-bar G have their lower edges rounded off at the ends to adapt them to slide smoothly across the top of the card or strip C, which latter acts more or less as a guide to control their 35 rocking motion on the arms 52. To maintain the arms g normally bearing against the card in this relation two light springs 58 are coiled around the pivot-screws 59 with their opposite ends bearing against the 40 sides of the levers 52 and the upper edges of the arms g. As a further positive means for holding the arms g down against the card or strip C, I provide an adjustable screw 60 extending through the end of a 45 finger 61 which is held in a slot 62 in the side of the arm 52. The screw 60 carries a check-nut 63 which may be released to allow its adjustment whereby the end of the screw can be set to bear against the 50 upper edge of the left-hand arm g when the gage G is drawn forward to the position 55 illustrated in Fig. 6. As shown in Fig. 10 the finger 61 is held in the slot 62 in the side of the arm 52 by a spring 61^a coiled around a screw 61^b which extends through the finger into the arm. This arrangement allows the finger 61 to be withdrawn from the slot 62 so that it may be rocked on the screw 61^b to raise the limit-screw 60; the purpose 60 of this arrangement being to provide for 65 tilting the gage G up out of the way to allow inspection or adjustment of the other parts of the mechanism adjacent thereto.

The forward movement of the gage G, or, in other words, its withdrawal in relation 70 to the ends of the raceways E, is effected synchronously with the feeding-motion of the plate H through means coördinated with the operating-mechanism thereof. Referring to Figs. 2 and 10, the rod J which carries the feed-plate H has a link 64 connected to its end. The link 64 is formed with a longitudinal slot 65 engaged by a screw 66 projecting from the side of a crank-arm 67 on the outer end of the rock-shaft G'. The 80 slot 65 is proportioned to allow for an initial, free movement of the link 64 with the feed-plate carrying-rod J before the arm 67 is moved therefrom. That is to say, when the feed-plate H first starts forward, to engage 85 its slots h' with the eyes b of the buttons B, the gage G will still remain at rest in the position shown in Fig. 5. When, however, the button-eyes have been seated in the ends of the slots h' the end of the slot 65 in the 90 link 64 will have come into engagement with the screw 66. At this juncture the link 64 acts through the screw 66 to rock the arm 67 and the gage-bar G is thereby withdrawn from the raceways to allow the buttons to be projected forward into setting 95 position, see Fig. 6. As shown in Figs. 5 and 6 the gage G is formed with a guardlip or ledge g' extending along its upper edge and this has the effect of preventing 100 the buttons B from riding up out of the slots h' in the feed-plate H or from canting rearwardly therein.

The button-setting means.—As the buttons are fed forward in rows by the feed-plate H they are affixed to the card C by forcing their eyes down through the latter as it rests on the feed-roll R. The grooves r in the roll R allow for the protrusion of the button-eyes from the under side of the 110 card C, and the small particles of cardboard or paper punched out are received therein; the grooves being cut deep enough to provide a generous clearance beneath the eyes, see Fig. 5. To prevent the grooves r from 115 filling up or becoming clogged with these extruded waste-particles, I provide a series of scrapers or clearers 68 held on a cross-rod 69 and formed with pointed blades 70 projecting into the grooves along the 120 roll.

The buttons B are pressed downwardly to force their eyes b through the card C by means of a set of plungers w carried by the reciprocating crosshead W, before mentioned. Referring to Figs. 1, 5 and 11, the plungers w are fitted to vertical bores in the crosshead W and are secured therein by the set-screws 71. Screwed into the upper 125 ends of the bores are adjusting-screws 72 130

which bear against the tops of the plungers *w* to locate them in position in the cross-head *W*. By releasing the set-screws 71 and adjusting the screws 72 the plungers *w* may 5 be set in position to bring their lower ends into alinement at the proper height above the roll *R* in accordance with the thickness of the buttons being operated upon. This provision for the adjustment of the plungers *w* adapts the machine for use with buttons of varying size or shape and also makes it possible to control the extent of projection of the button-eye through the card. For some purposes it is desirable to mount 10 the buttons on the card by merely projecting their eyes part way through the paper or cardboard so that their heads stand away therefrom; while in other cases it is required to seat the button-heads close against the 15 card. Usually the lower ends of the plungers *w* are recessed or concaved as shown at 74, Fig. 5, to adapt them to fit snugly over the rounded top or crown of the button-heads to provide a better contact therewith; 20 and where the contour of the heads varies to any great extent, with different styles of buttons, different forms of plungers are applied to the crosshead *W*.

The crosshead *W* is supported between the 25 frame-members *F*, *F'* of the machine with its ends fitted to slide in the vertical slots 3 in which the bearing-blocks 2 are held, see Figs. 1, 2 and 3. Fastened to the ends of the crosshead *W* by the studs 75 are two 30 eccentric-straps *q*, *q* bored to receive the eccentric-disks *Q*, *Q*, see Figs. 1 and 5. The eccentrics *Q*, *Q* are held fast on the drive-shaft *P* and during the rotation of the latter act through the straps *q*, *q* to reciprocate the 35 crosshead *W* vertically to give the required motion to the button-setting plungers *w*.

The raceway-clearing device.—The above described mechanism constitutes the complete apparatus for feeding the card or strip 40 and for supplying and affixing the buttons thereto, but to prevent any interruption in the feed of the buttons and to insure a continuous supply thereof throughout the operation of the machine, I have devised an additional, auxiliary device for preventing the 45 buttons from clogging the raceways. This consists of an agitator or vibrator for setting up a periodical vibration of the raceways to dislodge any of the buttons that 50 may be inclined to stick in the slots. Referring particularly to Fig. 3, a rockable lever 77 is pivoted on the end of the lower feed-roll shaft *S* which projects through the 55 side of the frame-member *F*, and is held in place by a collar 78, see also Fig. 1. This lever 77 is formed with a rounded, upper end adapted to be engaged by a lug or cam-projection 79 on the side of a disk 80, which latter is fast on the end of the drive-shaft 60 *P*. A spring 81 anchored to the frame-mem-

ber at *j'* acts to hold the end of the lever 77 bearing against the periphery of the cam-disk 80. The lever 77 is connected by a link 82 to an arm 83 fast on the end of a rock-shaft 84. The rock-shaft 84 is journaled in 70 a bearing 85, mounted on the foot of the frame-member *F*, and carries a detent-latch 86 at its opposite end. Pivoted on a rod 87 extending between the two frame-members *F*, *F'* is a yoke-like frame 88 constructed 75 with two opposite arms 89, 90 connected by the horizontal cross-bar 91, see Figs. 3 and 4. The cross-bar 91 carries a set of hammerpins 92 screwed into suitable holes along its length and held from turning by the check-nuts 93. The hammers 92 are equal in number to the whole number of raceways *E* on the machine and are spaced to bring their upper, rounded ends into position to strike against the under sides of the raceways. 80 Suitable springs 94 are anchored to pins 95 driven into the two end raceways *E* and are attached at 96 to the ends of the frame 88. A plate 97 is secured to one arm 89 of the frame 88 by means of a set-screw 98 extending through a slot 99, to provide for its adjustment laterally of the arm. On the lower side of the plate 97 is a lip or abutment 100, the edge of which is adapted to be engaged by the detent-shoulder 101 on the latch 86. 95 On the opposite arm 90 of the frame 88 is a plate 102, adjustably attached thereto by means of the set-screw 103 extending through the slot 104. The plate 102 is formed at its top with a pointed projection 105 adapted to be engaged by a wiper-collar 106 fastened on the cross-rod *J* which extends between the arms *J'*, *J'*. The wiper 106 acts against the pointed end of the plate 102 to depress the outer end of the frame 100 88 as the arms *J'* are oscillated back and forth by the shaft *K*. As the frame 88 is thus rocked downwardly on its pivot-rod 87 the detent-shoulder 101 of the latch 86 engages the lip 100 on the plate 97 to hold the 105 hammers 92 away from the raceways *E*. When, however, the lever 77 is moved outwardly against the tension of its spring 81, through the action of the lug 79 on the disk 80 riding across its end, the link 82 will 110 rock the detent-latch 86 to release the frame 88, whereby the springs 94 will cause it to impel the hammers 92 against the under sides of the raceways *E*. The sudden release of the detent-latch 86 causes an abrupt 115 motion of the frame 88 which thus acts through the hammers 92 to tap the raceways with a sharp blow. The extent of movement of the frame 88 is regulated by adjusting the position of the plates 97 and 102 and 120 hammers 92 and the timing of its action is controlled by the setting of the cam-disk 80 125 as more fully explained hereinafter.

Method of operation of the complete apparatus.—The machine is prepared for oper- 130

- ation by placing a supply of buttons in the hoppers and providing a strip or roll of sheet-material, such as cardboard, paper or the like, for delivery to the feed-rolls R, R'.
- 5 In applying the strip or card C to the machine its marginal edges are inserted in the guiding-grooves 12 of the side-cleats 13 and its leading edge fed forward between the peripheries of the upper feed-rolls R' and
- 10 bottom roll R by turning the feed-shaft S through the means of the hand-wheel Z, shown in Fig. 1. As before explained, the upper feed-rolls R' are pressed down into contact with the sides of the strip or card
- 15 C by the tension-springs s' and thereby exert a frictional grip to cause the paper to be fed ahead through the turning of the rolls in the direction indicated by the arrow a, Fig. 5. The buttons B are fed from the
- 20 hoppers to the raceways E and gravitate down the inclines thereof, guided by their eyes b sliding in the grooves e. The buttons are held from jumping up out of the raceway-grooves e by the overlying guard-strips E' and when the first buttons in each raceway reaches the stop-pin Y, at the lower end of the raceway, the whole series of buttons is held from further feeding movement, see Fig. 6.
- 25 30 After the strip C is in place between the feed-rolls R, R' and the raceways E have been filled with the buttons B as above explained, power is applied to the drive-shaft P to operate the machine continuously.
- 35 During the first cycle of operations of the several coördinated mechanisms, while the shaft P turns through one complete rotation, the stop-pins Y will be raised by the frame U' to allow the lowermost button B
- 40 in each raceway E to feed down into delivering position, as illustrated in Fig. 5. This upward movement of the frame U' is caused by the action of the springs 44 as the rollers v on the rods 42 ride into the depressions v' in the peripheries of the cams V. As before noted, this movement is very slight and occupies but an instant of time, so that immediately one set of buttons has been released by the stop-pins Y, Fig. 6, to allow them to
- 45 50 drop into delivering position as shown in Fig. 5, the pins Y are carried down again to engage the next set of buttons to hold them from feeding until the operation of setting the first row of buttons on the card
- 55 is completed. As the frame U' rises to withdraw the stop-pins Y it also raises the lifter-pins U, and these being hooked under the ends of the tension-springs or fingers T, as shown in Figs. 11 and 12, will act to raise
- 60 the fingers slightly to provide for a free movement of all of the buttons in the lower ends of the raceways E. As the first button in each raceway feeds into delivering position it strikes against the side face of
- 65 the gage G which, in the meantime, has been

carried into position beneath the setting plungers w as shown in Fig. 5. The lip g' on the edge of the gage-bar G prevents the buttons from tilting up out of place in the raceways E and after the feeding buttons 70 have assumed the position above described the fingers T are immediately allowed to spring back to again bear on the button-heads. In this manner the whole row of buttons at the delivery ends of the raceways 75 E are held in place with their eyes projecting down through the slots e in position to be engaged by the notches h' in the feed-plate H.

The feed-plate H is operated from the 80 rock-shaft K which receives its motion through the action of the rollers k on the arms K' riding on the cams O. As shown in Fig. 5 each cam O is formed with a considerable extent of its periphery o', about 85 one-half of its whole circumference or 180 degrees, which is concentric to the axis of the shaft P. As the rolls o ride over this portion o' of the cams the arms K' will receive no motion therefrom and hence the 90 rock-shaft K will remain at rest. During this period the feed-plate H is at the rearward end of its stroke where it dwells throughout substantially one-half of each rotation of the drive-shaft P, during which 95 time the buttons feed into place to be delivered from the raceways in the manner as above explained. As the buttons assume their delivering-positions, however, and the spring-fingers T return into contact with 100 their heads to hold them in place, the feed-plate H starts to slide forward beneath the raceways E to engage its slots h' with the eyes b of the buttons. This movement is effected through the action of the springs j 105 on the arms J', see Fig. 2, as the rolls k on the ends of the arm K' ride across the flattened faces o² of the cams O. After the plate H has moved forward a sufficient distance to seat the button-eyes b against the 110 ends of the slots h' in its forward edge, the gage-bar G will start to move forward with it. This forward movement of the gage G, or in other words its retraction from under the plungers w, is effected by the link 64 115 on the end of the plate-supporting rod J, see Fig. 2. As the end of the slot 65 in the link 64 comes into engagement with the stud 66 on the arm 67, it acts thereon to rock the shaft G' which, through the arms 120 52, see Fig. 5, swings the supporting-arms g to withdraw the gage G. In this manner the gage G is caused to move forward with the feed-plate H in such relation thereto that its side bears constantly against the 125 feeding buttons B to retain their eyes b firmly seated in the slots h' in the plate. As the buttons B are thus projected out from the ends of the raceways E into position beneath the setting-plungers w the latter start 130

to descend under the action of the cross-head *W* which is reciprocated in its bearings in the frame-members *F*, *F'* through the turning of the eccentrics *Q*.

5 Fig. 6 illustrates the feed-plate *H* at the forward end of its stroke and at this point the plungers *w* will have been brought down against the tops of the buttons as here shown. It will also be noted that the plate 10 *H* will have been tilted upwardly to a slight extent at its forward edge, due to the arcuate path of travel of its supporting rod *J*, and also that its underlying springs *I* will be pressed down against the sheet or strip 15 *C* to hold the latter against bending or buckling at its center. At the same time the edge of the plate *H* is beneath the gage-bar *G* and the latter is held with its side against the buttons *B* and its arms *g* pressed down 20 against the sides of the strip *C* through the action of the screw *60*. With the parts in this position it will be seen that the buttons *B* will be held firmly in alinement in a straight row extending across the top of the 25 card *C*. Now, as the plungers *w* continue to descend they will carry the buttons down with them, causing their eyes *b* to pierce the strip *C* to affix them in place thereon. As the eyes *b* are thus inserted through the 30 cardboard they extrude a portion of the material, while the edges of the openings will tend to cling to their sides. As shown in Figs. 5 and 6, this slight flanging out of the edges *c* of the openings in the card *C* 35 causes a binding or gripping effect on the eyes *b* whereby the buttons are anchored securely in place.

As the plungers *w* carry the buttons down against the card the feed-plate *H* rocks 40 downwardly with them, this action being provided for by the tilting of the plate on its pivot-rod *J*, against the tension of the springs *35*. After the button-eyes *b* have been inserted part way through the card, so 45 that the buttons are thereby held from lateral movement, the plate *H* is withdrawn. This action takes place as the rolls *k* on the arms *K'* ride up on the faces *o'* of the cams *O* and may be timed by adjusting the cams 50 rotatively of the drive-shaft *P*. It will be noted that the forepart of the plate *H* is tapered down to some extent where it underlies the buttons and in some cases it has been found of advantage to let this thin 55 edge remain beneath the buttons until after they are set. That is to say, when it is desired to affix the buttons to the cards with their heads spaced slightly above its top the plate *H* is not withdrawn until the 60 plungers *w* start to ascend. By adjusting the vertical position of the plungers *w* in the crosshead *W* and by regulating the action of the plate *H* to cause it to dwell beneath the buttons for a greater or less in-

terval any desired extent of protrusion of 65 the button-eyes through the card may be arrived at, although in most cases the button-heads are brought down flush against the top of the card as shown in Figs. 5 and 6.

As the plungers *w* are withdrawn after 70 setting one row of buttons the stop-pins *Y* and finger-lifting pins *U* are also raised to release the next set of buttons in the raceways *E*. Another cycle of operation of the parts then takes place to set the next row of 75 buttons in the manner as above explained. Meanwhile, the operating-mechanism for the feed-rolls *R*, *R'* comes into action so as to feed the strip *C* forward to a predetermined extent. Each time the shaft *P* makes 80 a complete rotation the crank-pin *18* acts through the link *L* to rock the lever *L'* to operate the pawl *N*, see Fig. 2. The pawl *N* is thus given a stroke sufficient to turn the ratchet *M* ahead a certain number of teeth 85 as determined by the throw of the crank-pin *18*. Through this means the shaft *S* is rotated to turn the feed-roll *R* and the rolls *R'* are rotated therefrom an equal extent by means of the gears *s*, *s*. By adjusting the 90 throw of the crank-pin *18* the rotation of the feed-rolls may be regulated as required to feed the card *C* forward to any desired extent, and in this manner the step-by-step advance of the card is regulated to cause 95 the buttons to be set in rows spaced equidistantly apart in any predetermined relation.

The machine operates continuously in the manner above explained to affix the buttons 100 to the card or strip *C*, row after row across its width, and each time the stop-pins *Y* are raised to allow a new set of buttons to feed into position the raceway vibrator mechanism comes into action as next explained: Referring particularly to Figs. 3 and 4, as the arms *J'* swing forward, to operate the feed-plate *H* to project the buttons from the raceways; the collar *106* on the rod *J* will wipe across the pointed end 105 *105* of the plate *102*. This action causes the frame *88* to be rocked downwardly on its pivot *87* and the plate *97* on its arm *89* will be carried down past the latch *86*. During 110 this time the lever *77* will be bearing against the concentric portion of the cam-collar *80* and hence the latch *86* will be in position to receive the lip *100* on the plate *97* beneath its detent-shoulder *101*. In this manner the frame *88* is locked and held against 115 the action of the springs *94* with its hammer-pins *92* retracted from the under sides of the raceways *E*. Now, as the shaft *P* continues to rotate and the cams *V* are carried around into position to effect the withdrawal of the stop-pins *Y*, see Figs. 5 and 120 6, the lug or projection *79* on the collar *80* will ride under the enlargement on the end 125

of the lever 77 to rock the latter to the left, as shown in Fig. 3. The movement of the lever 77 is communicated through the link 82 to rock the arm 83, and with it the shaft 84 and latch 86, thereby disengaging the detent-shoulder 101 from the lip 100 on the plate 97. As the frame 88 is thus released the springs 94 act to draw it upwardly with a quick motion to cause the hammers 92 to strike against the raceways E with a sharp impact. At this juncture the arms J' and rod J are in their rearward position, as illustrated in Fig. 3, so as not to interfere with the movement of the frame 88, and at the next forward movement of the arms the frame is carried down into position to be locked again. As before indicated the blows from the hammers 92 occur at a point just after the stop-pins Y have been raised and serve to vibrate or agitate the raceways E to dislodge any of the buttons that may be inclined to stick therein. Through this means the raceways are prevented from clogging and a continuous feed of the buttons insured for as long as the supply is maintained in the hoppers.

The whole machine is thus designed to operate automatically and continuously without attention on the part of the operator except to maintain the supply of the strip or card C and to replenish the supply of the buttons B. Although it is usual to supply the paper or cardboard to the machine in a continuous strip or ribbon, which may be cut into separate cards after the buttons are affixed thereto, if preferred, means might be provided for feeding the cards from a stack or pile in the manner employed on printing-presses. It is also to be noted that while I have herein illustrated my new apparatus as adapted for setting the buttons twelve in a row, this number being most convenient for counting them by the gross or great gross, if desired, the mechanism could be extended for carding them in rows of greater multiples. Obviously, the same mechanism could also be employed for attaching a single row of buttons to a band or tape and other adaptations could be arranged for as required. For instance, the improved button-feeding mechanism herein described and illustrated might be employed to advantage on various types of machines for performing different operations on buttons in the several arts of manufacture to which they are applied.

Various modifications might also be made in the construction and arrangement of the parts of the mechanism without departing from the spirit or scope of the invention; therefore, without limiting myself to the exact embodiment shown and described, what I claim is:—

1. In a machine for carding buttons, the

combination with a horizontally reciprocating plate provided with a plurality of slots for engaging a series of buttons by their eyes to feed them forward and support them in upright position above the card, of means coöordinated therewith for operating on the buttons to press them against the card to insert their eyes therethrough whereby to affix them in place thereon.

2. In a machine for carding buttons, the combination with a slotted feed-plate, of means for reciprocating said feed-plate in a substantially horizontal plane to adapt it to engage the buttons by their eyes to move them forward into position above the card, and means coöordinated therewith for acting on the buttons in series to force them down against the card to insert their eyes therethrough whereby to affix them in place thereon.

3. In a machine for carding buttons, the combination with a reciprocating feed-plate having a plurality of slots for engaging the buttons by their eyes to feed them forward into position above the card, of means engaging the buttons to hold their eyes against the ends of the slots in the feed-plate to aline them in a row across the card, and means coöordinated therewith for forcing the buttons against the card to insert their eyes therethrough whereby to affix them in place thereon.

4. In a button-carding machine, the combination with means for delivering buttons to the machine, of a horizontally reciprocating feed-plate having slots for engaging the buttons by their eyes to feed them forward from the delivering-means into position above the card, means engaging the sides of the buttons to aline them in a row across the feed-plate, and coöordinated means for affixing the buttons in position on the card by forcing their eyes therethrough.

5. In a button-carding machine, the combination with means for feeding a card or strip, of means for delivering a plurality of buttons into position above the card, a slotted feed-plate for engaging the buttons by their eyes to support them in a row across the card, means adapted to bear against the sides of the buttons to hold them in the slots in the feed-plate, and means coöoperating therewith for forcing the row of buttons against the card to insert their eyes therethrough whereby to affix them in position thereon.

6. In a button-setting machine, the combination with means for feeding a strip or card including a grooved feed-roll, of means for intermittently rotating the feed-roll, means for adjusting the rotation of the feed-roll to regulate the extent of feed of the card, means for feeding buttons into position above the card as it is fed by the feed-roll,

and means coöperating therewith for forcing the buttons against the card as it bears on the feed-roll to insert the button-eyes therethrough and into the grooves of the 5 feed-roll.

7. In a button-carding machine, the combination with a raceway for delivering buttons to the machine, of a reciprocating slotted feed-plate for engaging the buttons by 10 their eyes to project them forward from the raceway into position above the card at a single movement, and means coöperating therewith to press the buttons against the card while they are held in the feed-plate to 15 force their eyes through the card whereby to affix them in position thereon.

8. In a button-carding machine, the combination with a plurality of button-raceways, of a slotted feed-plate for projecting 20 the buttons in series from the raceway and into position above the card, means engaging the buttons for alining them in the slots of the feed-plate, and means coördinated therewith for pressing the row of buttons 25 collectively against the card to force their eyes therethrough whereby to affix them in position thereon.

9. In a button-carding machine, the combination with means for delivering a plurality of buttons, of a slotted feed-plate for 30 engaging the buttons by their eyes to project them from the delivering means in series, means for alining and positioning the buttons in the feed-plate after they have 35 been projected thereby, and means coöperating therewith to press the buttons against the card as they are held by the alining means to force their eyes through the card whereby to affix them in position thereon.

40 10. In a button-carding machine, the combination with a plurality of button-raceways, of a reciprocating slotted feed-plate for engaging the buttons by their eyes to project them from the raceways and support them above the card, means to press 45 against the buttons to force their eyes through the card, and means for withdrawing the feed-plate from beneath the buttons as their eyes are forced down through the 50 card, said means being adjustable to vary the timing of movement of the feed-plate to regulate the extent of protrusion of the button-eyes through the card.

11. In a button-carding machine, the combination with raceways for delivering buttons to the machine, of a reciprocable slotted feed-plate for engaging the buttons by their eyes to project them from the raceways into 55 position above the card, reciprocating means 60 for acting on the buttons to press them against the card to force their eyes therethrough, and means to withdraw the feed-plate from beneath the buttons during the setting operation, said means being adjust-

able to vary the timing of the withdrawal 65 of the feed-plate to regulate the extent of protrusion of the button-eyes through the card.

12. In a button-setting machine, the combination with reciprocable setting-means for 70 acting against the buttons, of a slotted feed-member coöperating therewith to engage the buttons by their eyes to carry them into the path of the setting-means, and positively-actuated means to withdraw the feed-member as the setting-means comes into action against the buttons, the synchrony of operation between the feeding-means and setting-means being adjustable. 75

13. In a button-carding machine, the combination with raceways for delivering buttons to the machine, of a reciprocating button-setting member for affixing the buttons to the card, a slotted feed-member reciprocable into position beneath the heads of the 85 buttons to engage their eyes to carry them into the path of the setting-member, and means to oscillate the feed-member back and forth in relation to the setting-member to carry the buttons the full distance into setting position at each stroke of said feed-member. 90

14. In a button-carding machine, the combination with an inclined raceway having a 95 slot for the button-eyes, of a feed-plate arranged beneath the raceway and slotted to receive the eye of the button as it issues therefrom to adapt its head to be supported thereon, means to reciprocate the feed-plate to project the buttons out from the raceway, 100 presser-means acting on the buttons to force their eyes through the card after they have been projected into position by the feed-plate, and means moving with the feed-plate to bear against the buttons to hold them in 105 erect position during the action of the presser-means.

15. In a button-carding machine, the combination with a series of inclined raceways 110 provided with guiding slots for the button-eyes, of a slotted feed-plate reciprocable beneath the ends of the raceways to engage the buttons by their eyes, means to operate the feed-plate to project the buttons out from the raceways in series, means for holding the buttons in the slots of the feed-plate during the feeding movement, and means 115 acting on the buttons carried by the feed-plate to insert their eyes through the card.

16. In a button-carding machine, the combination with a series of inclined raceways for receiving the buttons, of a slotted feed-plate arranged beneath the raceways to 120 adapt it to engage the buttons by their eyes to project them therefrom, means to reciprocate the feed-plate while allowing it to rock away from the raceways, independently-operated means moving with the feed-plate to 125

maintain the buttons in the slots of the latter, and means for acting on the buttons carried by the feed-plate to press them against the card to force their eyes therethrough

- 5 17. In a button-carding machine, the combination with means for feeding a card or strip, of raceways for feeding the buttons into position above the card, a slotted feed-plate for engaging the buttons by their eyes 10 to project them out from the ends of the raceways, means to reciprocate the feed-plate, and means acting on the buttons carried by the feed-plate to press them against the card to force their eyes therethrough.
- 15 18. In a button-carding machine, the combination with means for feeding a card or strip, of raceways for feeding the buttons into position above the card, a slotted feed-plate for engaging the buttons by their eyes 20 to project them out from the ends of the raceways, means to reciprocate the feed-plate, means acting on the buttons carried by the feed-plate to maintain them in the slots thereof, and means operating on the 25 buttons after they have been projected from the raceways to press them against the card to force their eyes therethrough.

19. In a button-carding machine, the combination with means for feeding a card or strip, of raceways for feeding the buttons into position above the card, a slotted feed-plate for engaging the buttons by their eyes to project them out from the raceways, means to operate the feed-plate, means for 30 holding the buttons in the slots of the feed-plate during their movement therewith, setting-means acting against the buttons carried by the feed-plate to force their eyes through the card, and means for withdraw- 35 ing the button-holding means as the setting-means comes into action.

20. In a button-carding machine, the combination with means for feeding a card or strip, of raceways for feeding the buttons into position above the card, a slotted feed-plate for engaging the buttons by their eyes to project them out from the raceways, a 40 gage-bar for normally maintaining the buttons in alignment at the ends of the race- ways, means to reciprocate the feed-plate, means to move the gage-bar with the feed-plate to retain the buttons in the slots thereof, and means operating on the buttons at the end of their movement with the feed- 45 plate to press them against the card to force their eyes therethrough.

21. In a button-setting machine, the combination with setting-means for acting on the buttons to insert their eyes through a card or strip, of a feed-member for projecting the buttons into operative position in relation to the setting-means, a gage-member for maintaining the buttons in erect position in the feed-member, and means for moving 50

the gage-member with the feed-member as 65 the buttons are fed into setting position.

22. In a machine for operating on buttons, the combination with a raceway for delivering buttons into the machine, of a member for holding the buttons in place at 70 the end of the raceway, a slotted feed-member for engaging the eyes of the buttons to project them out from the raceway, and independently-operated means for moving the button-holding member with the feed-member 75 to maintain the buttons in place in the slots of the latter during the feeding movement.

23. In a machine for operating on buttons, the combination with a plurality of button 80 raceways, of a gate-member normally held adjacent the ends of the raceways to retain the buttons in place therein, a slotted feed-member for engaging the eyes of the end buttons in the raceways to project them out 85 therefrom, means to operate the feed-member, and independently-operated means to move the gate-member with the feed-member to hold the buttons in place in the latter during the feeding movement. 90

24. In a machine for operating on buttons, the combination with a plurality of button-raceways, of a gate-member for holding the buttons in the ends of the raceways, a feed-member 95 engaging the eyes of the buttons to project them out from the ends of the raceways, oscillating-means for reciprocating the feed-member, and means connected therewith for moving the gate-member with the feed-member after the buttons have been engaged thereby to hold the buttons in place in the feed-member during the feeding movement. 100

25. In a machine for operating on buttons, the combination with a plurality of button-raceways, of a gate-member for holding the buttons in the raceways, resilient-means for maintaining the gate-member normally adjacent the ends of the raceways, a separate feed-member for engaging the eyes of the buttons to project them out from the ends of the raceways, and means to move the gate-member away from the raceways as the feed-member comes into engagement with the buttons to feed them therefrom. 110

26. In a machine for operating on buttons, the combination with a plurality of button-raceways, of a gage-bar, means to normally maintain the gage-bar in proximity to the ends of the raceways, a reciprocable feed-plate for engaging the buttons to project them out from the raceways, means to reciprocate the feed-plate, and a link connected with the reciprocating-means to move the gage-bar in unison with the feed-plate 120 after the latter comes into engagement with the buttons. 125

27. In a machine for operating on buttons,

the combination with a series of button-raceways, of a feed-member for engaging the buttons by their eyes to project them out from the raceways, means to actuate 5 the feed-member, a rock-shaft, arms supported thereon, a gate-member supported by said arms, resilient-means for rocking the shaft to maintain the gate-member in proximity to the ends of the raceways, and 10 means connected to the feed-member actuating-means to rock the shaft to withdraw the gate-member from the raceways as the buttons are projected therefrom.

28. In a machine for operating on buttons, the combination with the button-raceways, of a feed-member for projecting the buttons therefrom, means for holding the buttons from issuing from the raceways, means for withdrawing said holding-means, 20 and a separate auxiliary means for preventing the movement of the other buttons in the raceways while one set is being projected therefrom.

29. In a machine for operating on buttons, the combination with a button-raceway, of a spring-pressure finger adapted to engage the head of the end button in the raceway, means to feed the buttons out from the end of the raceway, and means to 30 raise the pressure-finger after the button has been fed from under it.

30. In a machine for operating on buttons, the combination with a series of raceways having guiding-slots for the button- 35 eyes, of spring-fingers overlying the slots in the raceways to adapt their ends to engage the end buttons therein, means for feeding the buttons out from the ends of the raceways, and means for periodically lifting 40 the spring-fingers away from the buttons after each operation of the feeding means.

31. In a machine for operating on buttons, the combination with a plurality of 45 raceways having guiding-slots for the button-eyes, of a series of spring-fingers overlying the slots in the raceways to adapt them to bear against the buttons therein, a series of lifter-pins having their ends 50 hooked under the edges of the spring-

fingers, and means to actuate the lifter-pins to raise the spring-fingers away from the buttons.

32. In a machine for operating on buttons, the combination with a plurality of 55 raceways having guiding-slots for the button-eyes, of a series of spring-fingers overlying the slots in the raceways to adapt them to bear on the buttons therein, a reciprocating frame, a series of lifter-pins carried 60 in said frame with their ends hooked under the edges of the spring-fingers, a series of auxiliary stop-pins slidably mounted in the frame, and resilient-means for maintaining the stop-pins in engagement with the buttons when the frame is in its lowermost position.

33. In a machine for carding buttons, the combination with means for feeding and affixing the buttons to the card, of a plurality of raceways in which the buttons slide, a series of hammers for striking against the raceways, a frame for actuating the hammers, means for periodically re- 70 tracting the frame, detent-means for holding the frame in retracted position, and means for releasing the detent-means.

34. In a button-carding machine, the combination with opposed feed-rolls for feeding a card or strip, of means to rotate said 80 rolls with an intermittent motion, means to adjust the extent of feeding motion of the rolls, means to feed buttons into position above the card fed by the rolls, and means to press the buttons against the card to 85 force their eyes therethrough.

35. In a button-carding machine, the combination with a lower feed-roll having 90 grooves in its periphery, of a pair of upper feed-rolls adapted to bear on the edges of a card or strip passing over the lower roll, means to rotate the rolls in unison with an intermittent motion, means to feed buttons into position above the card, and means to press the buttons against the card to force 95 their eyes therethrough and into the grooves of the lower-feed roll.

In testimony whereof I affix my signature.

GRANVILLE F. THAYER.
